UNITED STATES PATENT OFFICE.

MELVIN SOLOMON GROH, OF TORONTO, ONTARIO, CANADA.

PUMP.

Application filed February 3, 1922. Serial No. 533,906.

To all whom it may concern:

Be it known that I, MELVIN SOLOMON GROH, a resident of the city of Toronto, in the county of York, in the Province of 5 Ontario, Canada, have invented certain new and useful Improvements in Pumps, of which the following is the specification.

My invention relates to improvements in pumps and the object of the invention is 10 to devise a pump particularly designed to pump back the refrigerant gases into the condensing chamber of the refrigerator system.

A further object is to construct a pump 15 that will be more simple than those at present in use and which will have a fewer number of parts.

A still further object is to devise a pump 20 in which there will be an effective oil seal for the gas when being pumped therethrough.

My invention consists of a pump constructed and arranged all as hereinafter more particularly described and illustrated 25 in the accompanying drawing in which—

Fig. 1 represents a side elevation of a pump constructed according to my invention.

Fig. 2 is an elevational view of the other 30 side of the pump.

Fig. 3 is a vertical section through the line 3—3 Figure 7.

Fig. 4 is a vertical section through the line 4—4 Figure 3.

Fig. 5 is a vertical section through the line 5—5 Figure 3.

Fig. 6 is a vertical section through the line 6—6 Figure 3, showing the outer meshing spiral gears removed.

Fig. 7 is a similar view to Figure 6 showing the spiral gears in place, and

Fig. 8 is an end view.

Like characters of reference indicate corresponding parts in the different views.

1 is a portion of the pump casing which is illustrated and described in my co-pending application for improvements in refrigerating machines Serial Number 533,905, filed Feb. 3, 1922, as the cover plate of the 45 pump and condensing chambers, said portion 1 having an inwardly extending annular boss 2. 3 is a bearing plate register-

ing therewith. 4 is a second bearing plate. 5 and 6 are intermeshing spirally cut gears journaled by means of the spindles 7 and 8 respectively in the bearing plates 3 and 4. The outer spindle 8 is extended through a stuffing box 9 exteriorly of the portion of the casing 1 and is adapted to be driven by any suitable means. Thus the gear 6 becomes the driving gear and the gear 5 the driven gear.

The bearing plate 3 is provided with a semicircular housing 31 extending about the gears 5 and 6, the interior of the said housing being suitably curved to partially encase each of the gears, said interior wall of the housing engaging the crowns of the gear teeth. The bearing plate 4 is secured to the bearing plate 3 and the portion of the 70 casing 1 by means of the screw bolts 10.

11 is the gas inlet in the casing 1, the inner end of the said inlet registering with the inlet port 12 extending through the bearing plate 3 and so positioned as to communicate with the gears at a point on the housing side of the vertical centre line through the pump.

13 is an oil feed pipe communicating with the oil inlet ports 14 in the inner face of 60 the bearing plate 3 through the medium of the slots 15 in the inner face of the boss 2 of the casing portion 1.

The gears 5 and 6 are so mounted that the teeth engage each other first on the intake 65 end. Consequently as they are rotated past the inlet port 12 there will be a space between the root of the tooth on one gear and the corresponding crown on the other. Owing to the fact that the gears are spirally cut such space will gradually enlarge as the gears rotate further and consequently the gas from the intake port will fill this space.

As the gears rotate further the crown of 65 each tooth will engage the inner wall of the housing 31 and thus pocket the gas in the spaces between the teeth.

As the gears are rotated past the oil inlet ports 14 the oil will be forced into the spaces 100 between the teeth, and as it is under considerable pressure will compress the gas therein.

As the teeth revolve further their crowns

will disengage from the interior wall of the housing 31 and permit the gas in the spaces between the teeth to unite with the gas in the casing, which will be facilitated owing to the confined gas in the spaces between the teeth of the gear, prior to release into the casing being compressed by the introduction of the oil under pressure into such spaces to a pressure equal to the gas in the casing.

10 The pump is of course designed to be situated in a gas tight chamber.

As the gears revolve the majority of the oil which has been introduced into the spaces between the teeth is thrown off, leaving a thin film on the teeth thereon which acts as an oil seal when the spaces between such teeth again receive a further supply of gas.

In order to avoid gas pocketing, as the teeth reach the vertical centre line of the pump an aperture 16 is provided in the inner bearing plate 4. As the spiral gears rotate such gas is squeezed between the teeth from the intake port end towards the inner bearing plate end, and consequently passes through the aperture 16 in such plate 4.

From the above description it will be seen that I have devised a simple and effective pump which while particularly designed for pumping refrigerant gases can at the same time be used for pumping other gases, air or certain liquids if so desired.

Further I have devised a pump of the class described which will have comparatively few parts in comparison with such pumps at present in use.

What I claim as my invention is:

1. In a pump, the combination with the pump chamber casing, of intermeshing spirally cut gears, means for introducing the pumped fluid directly into the spaces between the intermeshing teeth at one end of the gears in a direction substantially parallel to the axes of such gears and means for sealing the fluid in the spaces between the teeth of the gears for a part of a revolution thereof.

2. In a pump, the combination with the pump chamber casing, of intermeshing spirally cut gears, means for introducing the pumped fluid directly into the spaces between the intermeshing teeth at one end of the gears in a direction substantially parallel to the axes of such gears, means for sealing the fluid in the spaces between the teeth of the gears for a part of a revolution thereof and means for introducing a sealing medium under pressure into the spaces between the teeth at a predetermined point during the revolution of each gear.

3. In a pump, the combination with the pump chamber casing, of intermeshing spirally cut gears, means for introducing the pumped fluid into the spaces between the intermeshing teeth at one end of the gears,

means for sealing the fluid in the spaces between the teeth of the gears for a part of a revolution thereof and means for releasing the pumped fluid from the spaces between the teeth of the gears prior to such teeth intermeshing.

4. In a pump, the combination with the pump chamber casing having a fluid inlet in the inner face thereof, of inner and outer spaced apart bearing plates suitably secured to the casing, one of the bearing plates having a fluid inlet port registering with the inlet in the casing, intermeshing spirally cut gears journalled between the bearing plates, said inlet port in the bearing plate so positioned with respect to the gears that the fluid to be pumped is admitted directly into the increasing spaces between the teeth as they disengage, means for driving one of the gears and means for engaging the crowns of the teeth of both gears during an equal part of their rotation from their point of disengagement with each other.

5. In a pump, the combination with the pump chamber casing having a fluid inlet in the inner face thereof, of inner and outer spaced apart bearing plates suitably secured to the casing, one of the bearing plates having a fluid inlet port registering with the inlet in the casing, intermeshing spirally cut gears journalled between the bearing plates, said inlet port in the bearing plate so positioned with respect to the gears that the fluid to be pumped is admitted directly into the increasing spaces between the teeth as they disengage, means for driving one of the gears, means for engaging the crowns of the teeth of both gears during an equal part of their rotation from their point of disengagement with each other and means for sealing the spaces between the teeth of both gears during that part of their rotation in which the crowns of the teeth are engaged.

6. In a pump, the combination with the pump chamber casing having a fluid inlet in the inner face thereof, of inner and outer spaced apart bearing plates suitably secured to the casing, one of the bearing plates having a fluid inlet port registering with the inlet in the casing, intermeshing spirally cut gears journalled between the bearing plates, means for driving one of the gears, a segmental housing extending between the bearing plates and its inner wall consisting of two arc shaped portions struck on radii substantially equal to the radii of the gear teeth crowns, the adjacent ends of the arc shaped inner wall portions of the housing constituting an inwardly extending pointed portion engaging the crowns of the gear teeth on the inlet side of such gear, and the fluid inlet port in the bearing plate positioned on the horizontal centre line of the pump between the apex of the pointed por-

tion and the vertical centre line of the pump.

7. In a pump, the combination with the pump chamber casing having a fluid inlet 5 in the inner face thereof, of inner and outer spaced apart bearing plates suitably secured to the casing, one of the bearing plates having a fluid inlet port registering with the inlet in the casing, intermeshing spirally cut 10 gears journalled between the bearing plates, means for driving one of the gears, a segmental housing extending between the bearing plates and its inner wall consisting of two arc shaped portions struck on radii substantially 15 equal to the radii of the gear teeth crowns, the adjacent ends of the arc-shaped inner wall portions of the housing constituting an inwardly extending pointed portion engaging the crowns of the gear teeth 20 on the inlet side of such gear, and the fluid inlet port in the bearing plate positioned on the horizontal centre line of the pump between the apex of the pointed portion and the vertical centre line of the pump the casing and adjacent bearing plate having sealing inlet passageways therethrough terminating in ports in the inner face of such bearing plate positioned so as to admit the sealing fluid to the spaces between the teeth 25 of the gearing during the portion of their revolution that they are in contact with the housing.

8. In a pump, the combination with the pump chamber casing having a fluid inlet 30 in the inner face thereof, of inner and outer spaced apart bearing plates suitably secured to the casing, one of the bearing plates having a fluid inlet port registering with the inlet in the casing, intermeshing spirally cut 35 gears journalled between the bearing plates, means for driving one of the gears, a segmental housing extending between the bearing plates and the interior wall thereof engaging the crowns of the teeth of both gears, the registering inlet in the casing and inlet 40 port in the outer bearing plate being positioned on the horizontal longitudinal axis of the pump and on the housing side of the vertical longitudinal axis, the inner face of 45 the casing having sealing fluid inlets registering with ports in the outer bearing plate, the centre of such ports being positioned on the pitch circles of the respective gear teeth.

9. In a pump, the combination with the pump chamber casing, of intermeshing spirally cut gears, means for introducing the refrigerant fluid when in the gaseous state into the spaces between the teeth as 50 they disengage from each other, means for retaining the gas in such spaces for a part of the revolution of each gear, means for introducing a sealing fluid under pressure into the gas filled spaces between the teeth 55 in a direction substantially parallel to the

axes of the gears, whereby the gas is compressed and sealed therein.

10. In a pump, the combination with the pump chamber casing, of intermeshing spirally cut gears, means for introducing the refrigerant fluid when in the gaseous state 60 into the spaces between the teeth as they disengage from each other in a direction substantially parallel to the axes of such gears, means for retaining the gas in such space 65 for a part of the revolution of each gear, means for introducing a sealing fluid under pressure into the gas filled spaces between the teeth in a direction substantially parallel to the axes of the gears, whereby 70 the gas is compressed and sealed therein.

11. In a pump, the combination with the pump chamber casing, of intermeshing spirally cut gears, means for introducing the refrigerant fluid in the gaseous state 75 into the spaces between the teeth of the gears as they disengage, means for compressing the gas in such spaces, means for subsequently releasing the gas into the pump chamber, and means for expelling any gas 80 in the spaces between the teeth in the pump chamber prior to the teeth intermeshing again.

12. In a pump, the combination with the pump chamber casing, of intermeshing spirally cut gears, means for introducing the refrigerant fluid in the gaseous state 85 into the spaces between the teeth of the gears as they disengage, means for compressing the gas in such spaces, unrestricted means 90 for releasing the gas into the pump chamber, and means for expelling any gas in the spaces between the teeth into the pump chamber prior to the teeth intermeshing 95 again.

13. In a pump, the combination with a pump chamber casing, of intermeshing spirally cut gears, means for introducing the refrigerant fluid when in a gaseous state 100 into the spaces between the teeth as they disengage from each other, means for retaining the gas in such spaces for a part 105 of the revolution of each gear, means for introducing a sealing fluid under pressure into the gas filled spaces between the teeth 110 whereby the gas is compressed and sealed, means for discharging the gas from the spaces between the teeth into the pump chamber casing, means for discharging the sealing fluid from the spaces between the teeth 115 under centrifugal force into the pump chamber casing in a direction substantially at right angles to the axes of such gears.

14. In a pump, the combination with a pump chamber casing, of intermeshing spirally cut gears, means for introducing the refrigerant fluid when in a gaseous state 120 into the spaces between the teeth as they disengage from each other, means for retaining the gas in such spaces for a part of 125

the revolution of each gear, means for introducing a sealing fluid under pressure into the gas filled spaces between the teeth whereby the gas is compressed and sealed, means for discharging the gas from the spaces between the teeth into the pump chamber casing, means for discharging the sealing fluid from the spaces between the teeth under centrifugal force into the pump chamber casing in a direction substantially 10 at right angles to the axes of such gears and prior to such teeth intermeshing again.

MELVIN SOLOMON GROH.
